(57) **CLAIM**

The ornamental design for an expandable light and the like, as shown and described.

DESCRIPTION

FIG. 1 is a front, left, top perspective view of an expandable light of an eight embodiment of the present invention in an expanded condition;

FIG. 2 is a front plan view of the invention as illustrated in FIG. 1;

FIG. 3 is a rear plan view of the invention illustrated in FIG. 1;

FIG. 4 is a left plan view of the invention illustrated in FIG. 1;

FIG. 5 is a right plan view of the invention illustrated in FIG. 1;

FIG. 6 is a top plan view of the invention illustrated in FIG. 1;

FIG. 7 is a bottom plan view of the invention illustrated in FIG. 1; and,

FIG. 8 is a front, left, bottom perspective view of the invention illustrated in FIG. 1.
